99,825

DESIGN FOR A MUDDLER

Thomas E. Pennington, Belmont, Calif.

Application January 25, 1936, Serial No. 60,808

Term of patent 7 years

To all whom it may concern:

Be it known that I, Thomas E. Pennington, a citizen of the United States of America, residing at Belmont, in the county of San Mateo and State of California, have invented a new, original, and ornamental Design for a Muddler, of which the following is a specification, reference being had to the accompanying drawing, forming a part thereof.

The figure is an elevational view of the article, showing my design.

I claim:—

The ornamental design for a muddler substantially as shown.

THOMAS E. PENNINGTON.
